RAIL-FASTENING DEVICE.

1,157,600.

Specification of Letters Patent.

Patented Oct. 19, 1915.

Application filed January 14, 1915. Serial No. 2,105.

To all whom it may concern:

Be it known that I, HENRY A. W. THOMASSON, a citizen of the United States, and a resident of 26 and Broad streets, Bellingham, in the county of Whatcom and State of Washington, have invented certain new and useful Improvements in Rail-Fastening Devices, of which the following is a specification.

10 My invention relates to improvements in fastening devices for securing railroad rails to the cross-ties; and the objects of my improvements are first, to provide a spike which, when driven into the tie obliquely to the rail flange and in a plane parallel to the rail web, has its head so inclined to its body that said head may be flatly seated on said rail flange; second, to shape the spike heads so that when the spikes are driven obliquely 15 in the tie in pairs, with the head of one spike over and against the head of the other spike of a pair, said former spike may retain the latter in place in said tie; third, to shape the spike heads so that they may present a 20 proper surface for striking with a driving maul and also have suitable projections under which the claws of a claw bar may engage for withdrawing said spikes from said tie; and fourth, to provide casings for embedding in concrete cross-ties suitable to receive my improved rail spikes.

I attain these objects by the devices illustrated in the accompanying sheet of drawings in which—

35 Figures 1 and 2 are two elevation views of my holding spike; Figs. 3 and 4 are two elevation views of my locking-and-holding spike; Fig. 5 is an elevation view showing one side of a rail and one end of a wooden 40 tie in which the rail is secured to the tie by my holding spikes two of which are used on the side of the rail illustrated. Fig. 6 is an elevation view of a rail and a wooden cross-tie in which the rail is secured to the tie by 45 both my holding and locking-and-holding spikes, one pair of which are used on the side illustrated. Fig. 7 is an elevation view of a rail and concrete cross-tie in which the rail is fastened to the tie by both my holding and locking-and-holding spikes, a pair of which are used on the side of the rail 50 illustrated; this figure further shows my improved casing embedded in the concrete; and

Fig. 8 is an elevation view of Fig. 7 as seen from the right of said figure.

Similar characters refer to similar parts of the several views. Certain parts are broken into in order to show those hidden thereby.

Figs. 1 and 2 show my holding spike comprising the body 1, similar to the body of the ordinary rail spike, and the T-head 3 transversely inclined to said body. The upper edge of this inclined head is flush with the spike body while the lower edge of said head 65 preferably overhangs said body. Also the bottom surfaces of both arms of said T-head are inclined upward at an angle with said body preferably equal to the angle of inclination of the top surface of the rail flange, 70 with which the spikes are to be used, to its bottom surface plus 90°. Furthermore the highest part of said inclined T-head is a flat surface or striking facet 3^b, or a surface which may become flat under the blows of 75 the driving maul, located over and normal to the longitudinal center line of spike body 1. The beveled surface 3^a inclines downward from surface 3^b to meet one side of spike body 1. The object of these flat surfaces will 80 be hereinafter explained.

Figs. 3 and 4 show my locking-and-holding spike comprising body 2 similar to spike body 1, transversely-inclined T-head 4 similar to head 3 except that the beveled surface 85 3^a of Figs. 1 and 2 is not formed on head 4. Head 4 has the striking facet 4^b at its highest part which is normal to and centrally over the longitudinal center line of body 2.

In Figs. 5, 6 is the cross-tie and 5 the 90 rail having head 5^a, web 5^b and flange 5^c. Here two of the holding spikes 1 are driven into the cross-tie 6 on one side of the rail 5 in the way in which I use them in a case where two spikes are desired on one side of 95 the rail but where it is not desired to use the holding and locking-and-holding spikes in locking relation.

It can be observed that because of the oblique direction of the spikes, 1, 1, Fig. 5, 100 in the tie 6, relative to rail 5, vibrations of and pressure on said rail which tend to lift its flange off of tie 6, will have less effect in withdrawing these obliquely driven spikes than if they were driven into the 105 cross-tie normal to said rail flange as is

usual. It can also be observed that the facets 3^a, 4^a provide a suitable surface on which to strike with the driving maul when driving the spikes, that the bottom surface 5 of one arm of inclined T-head 3 is flatly seated on the rail flange because the spike body 1, as shown, is driven into the tie at an angle with the rail flange equal to the angle between said spike body and said 10 transversely inclined T-head, and that the other arm of T-head 3 and the overhanging side of said head furnish a hold for a claw bar and further that this other arm of the T-head 3 can be used to lie over the rail 15 flange and hold the rail down when the said spike is turned side about before being driven in the cross-tie. In Fig. 5 the spikes 1 are arranged to show opposite sides so that attention is called to the fact that they 20 may be driven on either side of the rail and slanting in either direction as above described. On straight parts of the track it is usually sufficient to drive one of the spikes in the wooden tie on each side of the track, 25 for they are much more effective in holding the rails than are the ordinary straight-driven spikes. At the curves two spikes can be used, driven as in Fig. 5, or both may be driven to be slanting in the same direction— 30 which case is not illustrated—or better yet, in locking relation with each other as in Fig. 6. In Fig. 6, holding spike 1 is first driven into wooden tie 6 so that its head 3 rests flatly on the flange of rail 5. Then 35 locking-and-holding spike 2 is driven along side of spike head 3, as shown, until its head is also home on the flange of the rail. It will be observed that flat edge 4^a of head 4, now lies along side of and against 40 bevel surface 3^a, of spike head 3. Now since surface 4^a is directly in the line of travel of beveled surface 3^a, the presence of the locking-and-holding spike 2 as shown 45 in Fig. 6, will prevent spike head 3 from moving from its seat on the rail flange, and hence spike 2, when in this position relative to spike 1, locks the latter in place. And this is not only true when the head of spike 2 is seated on the rail flange, but is also true 50 even when spike 2 is partly out of the tie, as shown in dotted outline at 2' Fig. 6. Here the straight side of the body 2, lying against the beveled surface 3^a of head 3, serves to retain spike 1 in its place. Thus 55 it is apparent that the surface 3^a is needed to provide a proper bearing for the surface 4^a when the spikes are in operative position.

It may be noted that when driven home as shown in full lines in Fig. 6, both spikes 60 1 and 2 serve to hold the rail 5 on tie 6, and also that the free arms of T-heads 3 and 4 afford a claw hold.

In Figs. 7 and 8 each of casings 7, 7 is formed of a piece of pipe or tube bent into 65 the form of a triangle, and the open ends

of the pipe are tied together by the reinforcement 8. These triangular casings 7 are embedded in the concrete tie so that one may lie below and on each side of each of the rails as in Fig. 8. In Fig. 8 only one end of the concrete tie 10, and only one rail 5, are shown. The distance apart of these pairs of casings 7, is such that when the spikes are driven in said casings, as hereinafter explained, said rails will be retained at the proper gage. The spikes which I use with the casings 7, are in every respect similar to those used with wooden ties, as above explained, except that they are ordinarily shorter and are finished in a 70 tapered blunt end rather than sharpened as for the former use. Because of these slight differences the parts of these latter spikes have been given the same designating characters as those first above referred to. 75

The ties 10 are reinforced in a suitable manner. In Figs. 7 and 8, I show the preferred location of reinforcing rods 9, in order to increase the stability of casings 7. Other reinforcements can be added as desired. In Fig. 7, spike 2 is exposed by the removal of a portion of casing 7. In Fig. 8, one of spikes 2, is entirely exposed by the removal of one leg of one of the triangular casings 7, and a portion of one of the spikes 80 1, is also shown owing to the removal of a part of spike 2 and also a part of the other leg of the casing triangle. 95

With the triangular casings 7, 7 embedded in the concrete ties 10, as illustrated in Figs. 100 7 and 8, and described above, the fastening of rail 5, to these ties is a mere matter of first driving holding spikes 1, in one of the legs of each of said triangular casings 7, and then driving one of the locking-and-holding spikes 2, in each of the other of said legs, so that these spikes may be associated 105 as shown in Fig. 7.

The size of the tube used for the casings 7, is such that the corners of the spike's body 110 crowd themselves somewhat into the walls of said tubes, thus being quite firmly held thereby. In Fig. 7, as in Fig. 6, the part 4^a of head 4, of locking spike 2 lies over against the part 3^a of holding spike 1, so that spike 2, retains spike 1 in place in casing 7, also when spike 2 is partly removed to its dotted position at 2' Fig. 7, it still serves to retain spike 1 in its holding position. 115

It is customary to use straight pieces of pipe for spike casings in concrete ties, said casings being embedded normal to the upper surface of the ties. And into these tubes spikes of square cross section are driven to retain the rails in place. While I could effectively use such straight pieces of pipe set in the concrete tie at the proper angle for casings for my oblique headed spikes, I prefer the triangular form of casing as shown 120 because of its added strength and the 125 130

greater convenience of properly placing it in the form in which the ties are molded.

Having thus particularly explained my invention, what I claim as new and desire to 5 secure by Letters Patent is—

1. In a rail fastening device the combination with a rail, having a head, a web and a flange; and a cross-tie; of a rail spike having a body; a T-head the lower surface 10 of which is inclined to said body transversely of said head, one side of said head not protruding beyond said body, said spike driven into said cross-tie obliquely to said rail flange and in a plane parallel to said rail web with one arm of said T-head seated on said rail flange.

2. In a rail-fastening device the combination with a flanged rail, and a cross-tie, of two spikes, each having an inclined head, 20 and each driven into said tie obliquely to said flange with said heads seated on said flange and one of said heads lying over and against the other of said heads, substantially as and for the purpose specified.

3. In a rail-fastening device the combination with a rail, having a head a web and a flange; and a cross-tie; of two rail spikes each having a body and a transversely-inclined T-head, each of said heads having a 30 striking facet, and the head of the former of said spikes having the beveled surface 3^a, said spikes driven into said cross-tie obliquely to said rail flange and in a plane parallel to said rail web and each having 35 one arm of its T-head seated on said rail flange and one edge of the head of the latter spike lying over and against the said beveled surface 3^a on the head of the former spike.

4. In a rail-fastening device the combination with a concrete tie of a pair of spike 40 casings embedded therein, said casings comprising the ends of a pipe shaped into the form of a triangle.

5. In a rail-fastening device the combination with a flanged rail, and a concrete cross-tie, of a plurality of pairs of spike casings embedded in said tie, each of said pairs of casings comprising the ends of a pipe shaped into the form of a triangle, and a pair of rail spikes, having inclined heads, driven into 50 each of said pairs of casings with said heads seated on said flange and one of said heads of each of said pairs of spikes lying over and against the other of said heads.

6. In a rail-fastening device the combination with a rail having a head a web and a flange; a concrete cross-tie; and a pair of spike casings embedded in said cross-tie on each side of said rail flange, each casing oblique to said rail flange and in a plane 60 parallel to said rail web, the members of said pairs of casings diverging from each other from their tops downward; of a pair of spikes, having inclined heads, driven into each pair of said casings in such manner that 65 the head of one of said spikes of said pair lies over and against the head of the other of said spikes and the heads of both of said spikes seated on said rail flange.

Signed at Bellingham, in the county of 70 Whatcom and State of Washington, this sixth day of January, A. D. 1915.

HENRY A. W. THOMASSON.
